UNITED STATES PATENT OFFICE

97,871

DESIGN FOR A SODA FOUNTAIN CABINET

Dean C. Seitz, Lakewood, Ohio, assignor to Russ Seda Fountain Company, Cleveland, Ohio, a corporation of Ohio

Application June 11, 1935, Serial No. 57,221

Term of patent 14 years

To all whom it may concern:

Be it known that I, Dean C. Seitz, a citizen of the United States, residing at Lakewood, in the county of Cuyahoga and State of Ohio, have invented a new, original, and ornamental Design for a Soda Fountain Cabinet, of which the following is a specification, reference being had to the accompanying drawing, forming a part thereof.

In the drawing:

I claim:

The ornamental design for a soda fountain cabinet, as shown and described.

DEAN C. SEITZ.
